(57) **CLAIM**

The ornamental design for a mobile cart, as shown and described.

DESCRIPTION

FIG. 1 is a top and left side perspective view of a mobile cart, with movable carriers thereof in a first position, in accordance with a first embodiment of my new design; FIG. 2 is a left side elevational view thereof; FIG. 3 is a right side elevational view thereof; FIG. 4 is a front elevational view thereof; FIG. 5 is a rear elevational view thereof; FIG. 6 is a top plan view thereof; FIG. 7 is a top and left side perspective view of the mobile cart, with the movable carriers thereof in a second position; FIG. 8 is a top and left side perspective view of a mobile cart, with movable carriers thereof in a first position, in accordance with a second embodiment of my new design; FIG. 9 is a left side elevational view thereof; FIG. 10 is a right side elevational view thereof; FIG. 11 is a front elevational view thereof; FIG. 12 is a rear elevational view thereof; FIG. 13 is a top plan view thereof; and, FIG. 14 is a top and left side perspective view of the mobile cart, with the movable carriers thereof in a second position. The broken lines in the figures are for the purpose of showing environmental structure and form no part of the claimed design.
